(57) **CLAIM**

We claim the ornamental design for a winged down leg booster for a carburetor, as shown and described.

DESCRIPTION

FIG. 1 is a perspective view of a winged down leg booster for a carburetor showing the claimed design.

FIG. 2 is a rear elevation view of the winged down leg booster for the carburetor of FIG. 1.

FIG. 3 is a front elevation view of the winged down leg booster for the carburetor of FIG. 1.

FIG. 4 is a right side view of the winged down leg booster for the carburetor of FIG. 1.

FIG. 5 is a left side view of the winged down leg booster for the carburetor of FIG. 1.

FIG. 6 is a top plan view of the winged down leg booster for the carburetor of FIG. 1.

FIG. 7 is a bottom plan view of the winged down leg booster for the carburetor of FIG. 1; and,

FIG. 8 is a perspective view of the winged down leg booster for a carburetor of FIG. 1 shown in an exemplary carburetor. The broken lines used in the figures are for illustrative purposes only and form no part of the claimed design.
